UNITED STATES PATENT OFFICE.

ROBERT E. BAILEY, OF WYLIE, TEXAS.

WASHBOARD.

SPECIFICATION forming part of Letters Patent No. 653,848, dated July 17, 1900.

Application filed December 2, 1898. Serial No. 739,021. (No model.)

To all whom it may concern:

Be it known that I, ROBERT E. BAILEY, a citizen of the United States, residing at Wylie, in the county of Collin and State of Texas, have 5 invented a new and useful Washboard, of which the following is a specification.

The invention relates to improvements in washboards.

The object of the present invention is to improve the construction of washboards and to provide a simple, inexpensive, and efficient one which will afford an efficient rubbing-surface which will permit water to thoroughly drain from it after the operation of washing 15 has been completed.

The invention consists in the construction and novel combination and arrangement of parts hereinafter fully described, illustrated in the accompanying drawings, and pointed to out in the claims hereto appended.

In the drawings, Figure 1 is a front elevation of a washboard constructed in accordance with this invention. Fig. 2 is a longitudinal sectional view of the same. Fig. 3 is a transverse sectional view. Fig. 4 is a rear elevation of a portion of the washboard, illustrating the arrangement of the transverse drain-opening. Fig. 5 is an enlarged detail sectional view illustrating the arrangement of 20 the lower ends of the springs.

Like numerals of reference designate corresponding parts in all the figures of the drawings.

11 designate side pieces of the frame of the washboard, and these side pieces are connected by a back 2, extending from the upper cross-piece 3 to within a short distance of the lower end of the side pieces, which are extended to form legs in the usual manner. The back, 25 which is fitted between the side pieces, has its lower edge spaced from a bottom cross-bar 4, connecting the side pieces and having its front and rear edges flush with the front and rear edges of the said side pieces. The side 30 pieces are connected near their upper ends by an intermediate cross-piece 5, which is spaced from the top cross-piece 3 to form a soap-box.

Within the recess or space inclosed by the 35 side pieces and the cross-pieces 4 and 5 are arranged a series of parallel longitudinal

coiled springs 6, forming a rubbing-surface and having their end coils abutting against the said cross-pieces 4 and 5, and the lower terminals of the springs are extended rearward into the space 7, between the lower end of the back and the bottom cross-bar 4. This space forms a drain-opening, and by arranging the lower ends 8 of the springs between the back and the bottom cross-bar 4 a perfectly solid structure is provided and the durability of the washboard is greatly increased. The ends of the coiled springs divide the space 7 into a series of separate water-passages, as clearly illustrated in Fig. 3 65 of the accompanying drawings, and water is prevented from running from one end of the space to the other and is caused to pass directly through the same from the front of the washboard to the back thereof. 70

The coiled springs, which are expansion-springs, are placed in the recess or space of the frame of the washboard under tension, and the springs are prevented from bowing outward and are retained in the space or recess of the frame by longitudinal rods 9, extending through the spiral springs and engaging the same at the back thereof, whereby the springs are held securely against the back 2 of the frame of the washboard. The upper 80 and lower ends of the longitudinal rods are extended through the cross-bars 4 and 5 and abut against upper and lower transverse cleats 10 and 11, secured, respectively, to the upper face of the intermediate cross-bar 5 and 85 to the lower face of the bottom cross-bar 4. The side pieces are connected adjacent to the lower cleat 11 by a transverse rod 12, having its terminals suitably secured to the said side pieces. 90

It will be seen that the washboard, which is simple and comparatively-inexpensive in construction, possesses great strength and durability, and that the coiled springs, which form an efficient rubbing surface, are securely fastened to the frame, and that the transverse slot or space at the back of the same forms an efficient drain-opening. It will also be apparent that the lower terminals of the spiral spring by being interposed between the lower 95 end of the back and the lower cross-bar 4 divide the space or drain-opening and cause the 100

water to flow directly through the same, and they also support the parts by forming a solid structure.

What is claimed is—

- 5 1. A washboard comprising a frame having a space or recess at its front and provided at the bottom thereof with a transverse drain-opening, a series of longitudinal coiled springs arranged within the recess or space and having their lower ends extended rearward into the drain-opening and dividing the same into a series of separate passages, and the longitudinal rods passing through each of the coiled springs and located at the back of the coils and adapted to retain the said lower ends in the drain-opening, substantially as described.
- 10 2. A washboard comprising side pieces, a back connecting the side pieces, the lower cross-bar 4 spaced from the lower end of the back to form a transverse drain-opening, the intermediate cross-bar 5 connecting the side pieces near the top of the washboard, the longitudinal spiral springs interposed between the 15 said cross-pieces and having their lower terminals extended into the drain-opening and interposed between the bottom cross-piece 4 and
- 15 the lower end of the back, the rods extending through the coiled springs and through the cross-pieces 4 and 5, and the transverse cleats 30 arranged at the upper surface of the cross-piece 5 and the lower face of the cross-piece 4 and having the ends of the rods abutting against them, substantially as described.
- 20 3. A washboard comprising a frame having a space or recess at its front, a series of longitudinal expansion-springs arranged within the recess or space under compression, and having their end coils abutting against the frame, and the longitudinal rods passing 40 through each of the coiled springs, securing the same in the space or recess and preventing them from bowing outward, said rods having their terminals extended through the adjacent portions of the frame, substantially as 45 described.

In testimony that I claim the foregoing as my own I have hereto affixed my signature in the presence of two witnesses.

ROBERT E. X. BAILEY.
